WRENCH FOR USE WITH SKATEBOARDS

Albert J. Hess, Santa Ana, Calif.
(8837 Brookdale Drive, Garden Grove, Calif. 92644)

Filed July 7, 1975, Ser. No. 593,262

Term of patent 14 years

Int. Cl. D8—05

U.S. Cl. D8—26

FIG. 1

FIG. 2

FIG. 3

FIG. 4

FIG. 5

FIG. 6

FIG. 1 is a perspective view of my new wrench for use with skateboards;

FIG. 2 is a top view thereof;

FIG. 3 is a view in elevation of one side thereof;

FIG. 4 is a view in elevation showing the appearance of the front and the rear thereof;

FIG. 5 is a view in elevation of the other side thereof;

FIG. 6 is a bottom view thereof.

I claim:

The ornamental design for a wrench for use with skateboards, as shown and described.
